US00D996139S

(12) **United States Design Patent** (10) **Patent No.:** **US D996,139 S**
(45) **Date of Patent:** **** Aug. 22, 2023**

(54) **CONTAINER FOR LIQUIDS**

(71) Applicant: **Base Brands, LLC**, Atlanta, GA (US)

(72) Inventors: **Jamison Corey Harris**, Brookhaven, GA (US); **Patrick Spivey**, Atlanta, GA (US); **Kenneth Krealie**, Atlanta, GA (US)

(73) Assignee: **Base Brands, LLC**, Atlanta, GA (US)

(**) Term: **15 Years**

(21) Appl. No.: **29/765,189**

(22) Filed: **Jan. 6, 2021**

(51) LOC (14) Cl. **07-01**

(52) U.S. Cl.

USPC **D7/511**; D7/509

(58) **Field of Classification Search**

USPC ..... D7/507, 509, 510, 511, 523, 533, 392, D7/392.1, 396.1, 396.2, 300.1, 608, 900, D7/536, 535, 548, 300, 312-322; D9/500, 531, 516, 549, 447; D3/202 CPC A47G 19/22; A47G 19/2288; A47G 19/2205; A47J 41/0077

(57) **CLAIM**

The ornamental design for a container for liquids, as shown and described.

DESCRIPTION

FIG. 1 is a top perspective view of our new design for a container for liquids.

FIG. 2 is a top plan view thereof.

FIG. 3 is a bottom plan view thereof.

FIG. 4 is a front elevation view thereof.

FIG. 5 is a rear elevation view thereof.

FIG. 6 is a right side elevation view thereof; and,

FIG. 7 is a left side elevation view thereof.

The dot-dash broken lines depict the bounds of the claimed design and form no part thereof. The portions of the container for liquids shown in dot-dot broken lines form no part of the claimed design.

1 Claim, 3 Drawing Sheets
